SLUG CASTING MOLD

Ashton G. Stevenson, Chicago, Ill.

Application December 3, 1934, Serial No. 755,810

21 Claims. (Cl. 199—55)

One important purpose of the invention is to produce a mold which will be of simple and practicable construction and in which a line of short type, such as that suitable for use in multigraph, 5 fudge and/or similar short type machines, may be cast.

Another important purpose is to produce a mold for the casting of a slug which includes a separable section containing a line of short type 10 and which mold will be applicable to the mold wheel of any standard line casting machine without calling for any alteration or change in the structure of said wheel or in the mechanism employed in coaction therewith in casting the standard slug with its line of type.

A still further purpose is to provide a mold for the casting of a line of short type which not only may be applied to any machine for the casting of a slug with its line of type of standard size 20 and, moreover, will be of simple and most practicable construction, and will not be liable to get out of order and particularly will not call for special expert care upon the part of the operator.

25 In the casting of standard sizes of slugs the molds employed are composed of relatively immovable members but in casting slugs for a line of short type the members of the mold must be relatively movable and hence it has been found in practice with prior proposals that crevices or 30 cracks are formed into which the molten metal will find its way and will interfere with the relative movements of the parts of the mold into the position they should occupy in the casting operation.

Another important purpose of my invention, therefore, is to so construct the relatively movable members of the mold as to eliminate all possibility of the molten metal congealing within any 40 crack, crevice or other space where it would interfere with the closing of the two members of the mold into the precise relationship they must occupy in producing perfect slugs.

A still further purpose is to so construct the 45 two parts of the mold that in the initial movement of one member of the mold relatively to the other in opening the mold will coact with the commonly employed ejector in the operation of ejecting the slug.

50 Yet another important purpose is to provide the mold itself with means of self-locking nature, that is to say, to provide a mold comprising two relatively movable members provided with complementary elements which are brought into engagement one with the other in the closing of

the mold and when so engaged coact in effectively locking the members in their closed relation against all tendency to an accidental opening relative movement thereof.

An additional purpose is to provide a mold, 5 comprising relatively movable members and a means which is placed under tension in the relative movement of said members to open position and will coact in a most effective manner positively to effect relative movement to closing position.

Still another purpose of the invention is to provide a mold for casting a slug of standard size having a line of weakness to provide a separable short type section formed at opposite sides with 15 aligning grooves, and which slug will be further characterized in that one surface of its main body portion will be bevelled from front to rear along a line relatively to the upper and lower surfaces of the short section as to facilitate the 20 ejection of the complete slug from the mold.

These several purposes and others which will be evident to those persons familiar with the invention in its relation to prior proposals with respect to this type of slug-casting molds are embodied in the structures exemplified by the accompanying drawings, wherein like characters of reference denote corresponding parts in the several figures.

In said drawings:

Fig. 1 is a front elevation of a mold embodying novel features which constitute this invention;

Fig. 2 is a view showing the rear surfaces of the mold with certain contiguous portions of the cap and base broken away to disclose the pivot 35 pins, one of said pins being shown in section and the other in side view, this figure, also showing, in section, the screws which attach the mold to the mold wheel;

Fig. 3 is a vertical section on the line 3—3 of 40 Fig. 1, to show the relative position of the base and cap of the mold, with the slug therein, prior to the beginning of the ejecting operation on the slug;

Fig. 4 is a view similar to Fig. 3, but showing 45 the relative position of the mold members in the initial part of the ejecting movement of the slug;

Fig. 5 is also a view similar to Fig. 2, but shows a relative position of the parts when the slug has been nearly completely ejected; 50

Fig. 6 is a detail perspective view of the cap member of the mold;

Fig. 7 is a detail perspective view of the base member of the mold, showing certain parts thereof separated from said member; 55

Fig. 8 is a view in perspective of the complete slug as formed in the mold;

Fig. 9 is a view in perspective of the short type slug, that is, the face portion thereof after it has been separated from the base;

Fig. 10 is a vertical section on a line through the mold corresponding to the line 10—10 of Fig. 1, but showing a part of the mold wheel and the mold applied thereto;

Fig. 11 is a similar section showing a part of the mold wheel to which the mold is applied, on a line of section corresponding to the line 11—11 in Fig. 1;

Figs. 12, 13 and 14 are detail views of certain modifications wherein the cap member of the mold is slideable bodily at an upward and forward inclination, instead of having pivotal movement, relatively to the base member; Fig. 12 being a view of one end of the thus modified mold, showing a portion of the base member broken away; Fig. 13 being a vertical section on the line 13—13 of Fig. 12 and Fig. 14 being a detail representation, in perspective, of the end of the cap member.

While the illustrated embodiments will be hereinafter minutely described, it should be understood at the outset that the invention is not restricted to the precise details of said embodiments and, on the contrary, may be otherwise and variously embodied without departing from its spirit as defined in the appended claims.

Referring to the embodiment shown in Figs. 1—11, inclusive, A designates the base and B the cap of the mold, between whose confronting surfaces the slug in its complete form shown in Fig. 8 is cast.

In this particular embodiment the cap B is mounted near its rear surface and at its opposite ends upon correspondingly positioned pins a, a which project toward each other from the ends of the base A and said cap turns pivotally about said pins in its movements in opening and closing the mold.

The cap B is formed at opposite ends of its casting surface with projections, 10, 10' which form closing members at the ends of the casting space between the base and cap, and the base A is formed with recesses 11, 11' in which said closing members are seated when the cap is in closing relation with respect to the base. The ends of the face of the cap adjacent said closing members 10, 10' are formed with recesses as shown respectively at 10^a, 10^b in Fig. 6, and its face is provided with a rigid projection 12 whose upper end is fastened in the recess 10^a with one of its edges abutting against the projection 10 and its outer surface substantially flush with the face of the cap. This rigid projection extends downward from said recess and has a bevelled lower edge 12^a. The face of the base B is formed with a recess 13 which is so arranged that it will form a seat into which the portion of the projection 12 which extends from the cap is mounted with its outer surface slightly rearward of the plane of the face of the base when the cap is in its said closed relation. The face of the cap, at the end thereof opposite the projection 12, is provided with a resilient finger 14 whose upper end is fastened in the recess 10^b with its edge abutting against the side of the closing member 10' and its outer surface substantially flush with the face of said closing member. This resilient finger projects downward from the cap.

The face of the base is also provided with a resilient finger 15 positioned to engage and exert pressure upon the forward surface of the projec-

tion 12, said projection and resilient finger thereby coacting to lock the cap in its proper casting relationship with respect to the base during the casting operation while permitting the cap to be turned pivotally to permit ejection of the cast slug. This resilient finger is mounted in a recess 15' formed in the face of the base A and said base is also formed at the end of its face opposite said recess 15' with an additional recess 16' in which is mounted a resilient finger 16 whose end is superimposed on the free end of the resilient finger 14.

In the movement of the cap B to its open position the resilient finger 15 and the resilient fingers 14 and 16 are placed under tension which becomes effective to return the cap automatically to its closed position as soon as the cast slug has been ejected. In order that this return may be positive and uninterrupted the fingers 15 and 16 are of varying lengths and engage the projection 12 and finger 14 respectively at places which are not in horizontal alignment one with the other. Thus, the tension exerted upon the cap is at different places in the arc of movement of the pivoted cap, whereby all tendency of stall- 25 or stopping of the movement of the cap before it has fully returned to its closed position is overcome.

Since the spring fingers 15 and 16 are set within corresponding recesses 15' and 16' in the opposite ends of the base A and have their outer surfaces substantially flush with the corresponding surface of said base and since the projection 12 and spring finger 14 are similarly arranged with their outer surfaces substantially flush with the face of the cap, there will be no interference presented by these elements to a tight contact or engagement of the face of the mold with the matrices in the casting operation.

The base member A has its face formed, as usual, with alignment grooves 17, 17' and has along its upper longitudinal portion a rearward projection 18, which also is usual and adapts the base member to be seated in the mold pocket formed in the mold wheel. The pivot pins a project longitudinally toward each other from said rearward projection 18.

The cap B has its lower rear edge formed with a projection 19 and forward of said projection is formed with a second projection 19'. These projections are spaced from each other to provide a casting face 20 between them. These projections have oppositely inclined surfaces presented toward each other, the forward surface of the projection 19 being inclined rearwardly and the rear surface of the forward projection 19' being inclined forwardly from its upper end. The projection 19' is arranged to form the line of weakness (x') extending from end to end of the slug X, as is usual, but the projection 19 definitely has an ejecting function with respect to the slug, as will hereinafter be more particularly pointed out. From the rear surface of the upper end of the projection 19 the corresponding surface 21 of the cap is bevelled forwardly toward the top of the latter to prevent interruption, as by the ejector-blade support of line casting machines, for example, of the opening movement of the cap.

The casting surface of the cap is also formed with a longitudinal rib 22 which is spaced from the forward side of the projection 19' and with a longitudinal shoulder 23 forward of said rib. The complementary casting surface of the base A comprises a casting face 24, which cooperates 75

with the surface 20 of the cap B in forming the main body of the slug, and also comprises a rib 25, which is arranged forward of and is spaced from said face 24, and a shoulder 26 forward of said rib.

It will be evident that the ribs 22 and 25 of the cap and base, respectively, together with the depressions separating said ribs from the casting faces 20 and 24 and also together with the shoulders 23 and 26 all cooperate in forming the slug X (shown complete in Fig. 8 and in section in Figs. 3, 4 and 5). It also will be apparent that the line of weakness (x') is provided to facilitate the separation from the main body of the slug 15 of that part x upon which the type faces are formed and which part x constitutes the line of short type for use in the printing operation. This separation, as is usual, is made after the slug in its complete form has been cast and ejected 20 from the mold.

The body of the slug is characterized, in part, in that its lower or back face is bevelled from the line of weakness x' to its rear edge 27 so that if said slug were laid upon a flat surface it will 25 make contact with said surface only along the lines of its said rear edge and its forward edge 28, the intermediate portion of the slug being free from contact with said surface. This particular feature of the slug adapts it to the use 30 of all standard matrices with their standard alignment, thereby overcoming any necessity of changing the alignment of the standard matrices or of the machine with which said matrices are employed. In order to produce this bevel the 35 casting face 24 of the base A of the mold is correspondingly inclined upwardly from its back edge 28 for a distance equal to that between the back edge of the slug and the line of weakness x', namely, to the edge 29.

A further characteristic feature of the body 40 of the slug is the formation of the upper surface of its rear end with a bevel 30. This bevel 30 is formed by the projection 19 of the cap B and is so correlated with said projection that in the 45 movement of the cap to open position the projection will act upon said bevelled surface to move the slug to a partly ejected position, the remainder of the ejecting movement being derived from the ejector-blade which is standard 50 upon all line casting machines and is indicated at Y in Fig. 5.

The projections 19, 19' and casting face 20 of the cap B have their ends in abutting relationship with the inner surfaces of the closing members 55 10, 10' at the opposite ends of the casting space and the recesses 11, 11' in the base A in which said closing members operate in opening and closing the mold, are in communication with the grooves or channels 31, 31' which form sumps 60 or chambers in said base below the lower surfaces of the inner sides of the respective closing members. Hence, it will be seen that if any metal seeps between the opposing surfaces of said closing members and the casting face 24 of the 65 base in the casting operation it will be automatically freed by the wiping action of the closing members in the relative movement of the cap and base and will fall into the corresponding chamber 31 or 31' from which it may be subsequently removed in any appropriate way. Thus, 70 all liability of interference of movement of the cap to its full closing relationship with the base due to the presence of metal between opposing surfaces outside the casting space, is avoided.

It will be understood from the foregoing that

the mold is specially formed not only for the casting of a slug of standard size having a line of weakness extending longitudinally thereof to provide a section which is severable from the main body of the slug and has type faces along one surface, said section thereby constituting a line of short type, but, moreover, is specially formed to adapt it to be applied to the mold wheel of any standard line casting machine without requiring any change in the construction of 10 said wheel or in the mechanism which operates the wheel, including the melting pot and the type matrices with their operating means, which likewise need not be changed in adapting the machine to the use of this mold. It is well understood that the mold wheel of such a machine is formed with a series of chambers, usually four in number, in which a like number of molds for casting type of different sizes are commonly mounted, respectively. In the operation of the 20 machine, the wheel is turned through one-fourth of a complete revolution to bring the particular mold which is to be employed to the station at which it is connected to the melting pot at one side of the mold and operatively related to the 25 matrices at the other side of the mold, which melting pot and matrices are brought into operative relationship with the mold automatically at predetermined times in the movement of the wheel. During the operation, the wheel is moved 30 bodily to bring the face of the mold into a close union with the matrices and when this union has been effected the melting pot is moved into a close union with the back of the mold and the metal from said pot is then discharged into 35 the casting space in the mold through a series of openings which have been aligned with said casting space. When the cast has been made the melting pot is caused automatically to recede from the back of the mold and the wheel is caused 40 automatically to recede from the matrices. Said wheel is then rotated throughout three-fourths of a revolution, back to the starting station, and at a predetermined time in the latter part of its movement the mold is opened by appropriate 45 means and the formed slug is ejected therefrom, through the medium of an appropriate ejecting blade. At a predetermined timed relation with respect to the rotative movement of the mold wheel the matrices are automatically returned 50 to their former position and the mold is again closed. During the complete operation with respect to one mold the remaining molds on the mold wheel are not used and when they are to be used, respectively, a different set of matrices 55 is employed and the phases of operation hereinbefore set forth are carried out, but this time the different selected mold, of course, is the one which is brought into operative relationship with the matrices and with the melting pot. The particular mechanisms employed in effecting these phases of operation form no part of my invention and for that reason, and also because they are well understood in the art, are not herein 60 illustrated. The drawings, however, show a part 65 of the mold wheel, designated Z, in Figs. 3, 4 and 5 with my mold applied thereto and, as already stated, show also a part of an ejector blade at Y in Fig. 5.

It will be noticed that the base A of the mold 70 is formed to adapt it to said wheel and is stationarily secured to the latter by bolts 32. Hence, relative movement between the base and cap of the mold is effected by moving the cap in opening and closing the mold. In order that this 75

may be effected, means of suitable nature are provided by which the cap is forced to its open position at a predetermined place in the rotative movement of the mold with the mold wheel.

5 A device, such as the stop pin 33 arranged in the path of movement of the mold and in position to engage the cap and force the latter backward into its open position, provides a suitable means for the purpose. In order that this device 10 may be inoperative with relation to the remaining molds on the mold wheel it is of resilient nature so that it will yield upon contact with said remaining molds, and to this end the stop pin 33 when employed is provided with a spring 34 15 here shown as mounted in the interior thereof. It will be understood, however, that the mold cap B may be opened by any appropriate means or in any appropriate way, but the illustrated stop pin is simple and practicable and hence 20 preferred.

As hereinbefore stated the initial part of the opening movement of the cap B is transmitted to the rear end of the slug through the projection 19, and thereby initiates the ejection of 25 the slug, which ejection is completed by the ejector-blade Y. It will be noticed that in the ejecting movement of the slug it travels in an upwardly inclined path upon the correspondingly inclined casting face 24 whereby its forward end 30 is thereby raised sufficiently to free the rib which extends longitudinally along the rear side of the section x of the slug from the groove in the base A in which said rib has been formed. This movement of the slug is important since the base 35 A is stationary and the section x is of short-type nature.

While the cap B is being opened the resilient fingers 14, 15 and 16 are placed under tension (the fingers 14 and 16 having a mutual tensioning relationship and the finger 15 being tensioned by the locking projection 12, as hereinbefore explained) and thereby act to return the cap to its closed position positively and with absolute certainty and to lock the cap releasably 45 in its said closed position.

It will be understood that this mold may be substituted for any mold employed upon the mold wheel for making a slug of standard relatively long type style, and that it is not impracticable 50 to mount a plurality or series of these molds upon the wheel, for making lines of short type of different sizes, respectively.

In the modification shown in Figs. 12, 13 and 55 14 the cap, indicated at B^x in these figures, is mounted to have movement bodily in an upward and forward direction, instead of pivotally, in opening the mold, and to have movement in a downward and rearward direction gravitationally in closing the mold. The base in this particular embodiment is marked A^x. As here shown, the end of the base A^x is formed with a recess a^x which forms a guiding channel within 60 which travels a pin b^x projecting from the corresponding end of the cap B^x. It will be understood that opposite ends of the cap are provided with such pins and opposite ends of the base are provided with such channels. Since in this construction the cap will return to its closed position 65 gravitationally, it is considered to be unnecessary to employ the resilient fingers illustrated and described with respect to the other embodiments of the invention. In all other material respects, both embodiments are, or may be, alike.

70 75 Having thus described the invention what I

believe to be new and desire to secure by Letters Patent, is:—

1. A slug-casting mold comprising a base adapted to be secured stationarily to the face of a mold wheel forming part of a line casting 5 machine, a cap, means mounting said cap for opening movement in an upward and rearward direction, said base and cap having their surfaces adjacent each other complementarily formed to provide a casting space which includes 10 means for forming a line of weakness longitudinally of the slug and adjacent one side of the latter together with an aligning groove substantially parallel with said line of weakness, in combination with means operable against said 15 cap to impart opening movement thereto.

2. A slug-casting mold according to claim 1 in which the casting face of the base is inclined to cause the slug being ejected to traverse an upwardly inclined path. 20

3. A slug-casting mold comprising relatively movable members having complementary casting surfaces formed to provide a casting space, one of said members having a projecting portion arranged to initiate ejecting movement of the 25 cast slug relative to the members upon movement of said member relatively to the other member.

4. A slug-casting mold comprising a base, a cap movable relatively to said base in opening and closing the mold, said base and cap having 30 complementary casting surfaces, and said cap having a projection which forms a part of its casting surface, said projection being movable toward the base through opening of the cap to initiate ejecting movement of the cast slug. 35

5. A slug-casting mold according to claim 4 in which the movement of the cap is about a longitudinal axis adjacent the rear face thereof and the said projection is adjacent the axis of said movement. 40

6. A slug-casting mold according to claim 4 in which the opening movement of the cap is bodily in an upward and forward direction. 45

7. A slug-casting mold comprising a relatively movable base and cap respectively provided with elements coacting to automatically maintain the cap yieldably in closed position with respect to the base, one of said elements being a rigid projection and the other a spring finger whose free end has bearing upon the outer face of said projection. 50

8. A slug-casting mold comprising a relatively movable base and cap and having automatically operative closing and holding elements including resilient fingers placed under tension in the 55 relative movement of the base and cap to open position.

9. A slug-casting mold comprising a relatively movable base and cap, one of which has its opposite ends provided with a pair of resilient 60 fingers and the other has its opposite ends respectively provided with a rigid projection and a resilient finger, the resilient fingers at one end of the base and cap having bearing one upon the other and the rigid projection and resilient finger at the other end of the base and cap having bearing one upon the other, said fingers and projection coacting to close the mold and maintain the same releasably in closed condition. 65

10. A slug-casting mold according to claim 8 in which the closing and holding elements are seated in recesses in the base and cap and have their outer surfaces substantially flush with the faces of said base and cap. 70 75

11. A slug-casting mold comprising a base and a cap movable relatively to each other in opening and closing the mold, said base and cap having complementary casting faces, one of 5 which is formed to impart initial ejecting movement to the slug relatively to the base and cap in the relative movement of the base and cap to the open position thereof.

12. A slug-casting mold comprising a stationary base and a cap having pivotal movement relatively to the base in opening and closing the mold, said base and cap having complementary casting faces and said cap having as a part of its casting face a projection movable closer to the 15 base to impart initial ejecting movement to the slug relative to the base and cap in the pivotal movement of the cap to its open position.

13. A slug-casting mold according to claim 11 in which the complementary casting faces of 20 the cap and mold are relatively shaped to form a slug having a line of weakness extending longitudinally thereof and also having upper and lower aligning grooves forward of said line of weakness.

25 14. A slug-casting mold comprising a stationary base and a cap movable relatively to the base in opening and closing the mold, said base and cap having complementary casting faces relatively shaped to form a slug having a line of weakness 30 extending longitudinally thereof and also having spaced ribs on both its upper and lower surfaces forward of said line of weakness, and wherein the casting face of the base is inclined forwardly and upwardly toward said line of weakness.

35 15. A slug-casting mold comprising a base and a cap movable relatively to each other in opening and closing the mold, said base and cap being relatively formed to provide a casting space between 40 their confronting surfaces and having coacting closing surfaces at the ends of said casting space, and said coacting surfaces of the base and cap being relatively arranged to cause any metal deposited thereon to be wiped therefrom by the rel-

ative movement of the base and cap, and chambers arranged to receive metal thus wiped from said surfaces.

16. A slug-casting mold according to claim 15 in which the chambers extend from the face to 5 the back of the mold and have their ends open to said face and back, to facilitate removal of metal therefrom.

17. In a machine for casting printer's slugs having a line of type upon the face thereof, the 10 combination with an intermittently rotative mold wheel, of a mold carried by said wheel and comprising a base substantially immovable relatively thereto and a cap movable relatively to the base and wheel, said base and cap having their 15 confronting surfaces formed to provide a casting space including means for forming the slug with a severable section to constitute a line of short type, means arranged to automatically move the cap to its open position at a predetermined place 20 in the rotation of the wheel and means operative automatically to eject the formed slug from the thus opened mold.

18. A structure according to claim 17 in which the means for opening the cap is of resilient 25 nature.

19. A structure according to claim 17 in which the means for opening the cap comprises a spring-pressed pin which acts as a stop in the path of 30 movement of the cap.

20. A printer's slug having a line of weakness extending longitudinally thereof to provide a severable section having a line of type surfaces thereon, said section also having aligning grooves in its upper and lower faces and said slug having 35 its lower surface bevelled downward from the line of weakness to the longitudinal edge of the slug opposite the severable section.

21. A printer's slug according to claim 20 in which the rear longitudinal edge of the slug is 40 bevelled in an upward and forward direction.

ASHTON G. STEVENSON.
